N. W. CUMMINS.
HOOD FASTENER FOR AUTOMOBILES.
APPLICATION FILED, MAY 27, 1914.

1,140,503.

Patented May 25, 1915.

UNITED STATES PATENT OFFICE.

NORMAN W. CUMMINS, OF BRIDGEPORT, CONNECTICUT, ASSIGNOR TO THE BURNS & BASSICK COMPANY, OF BRIDGEPORT, CONNECTICUT, A CORPORATION OF CONNECTICUT.

HOOD-FASTENER FOR AUTOMOBILES.

1,140,503.

Specification of Letters Patent. Patented May 25, 1915.

Application filed May 27, 1914. Serial No. 841,204.

To all whom it may concern:

Be it known that I, NORMAN W. CUMMINS, a citizen of the United States, residing at the city of Bridgeport, county of Fairfield, State of Connecticut, have invented certain new and useful Improvements in Hood-Fasteners for Automobiles; and I do declare the following to be a full, clear, and exact description of the invention, such as will enable others skilled in the art to which it appertains to make and use the same.

This invention relates to certain new and useful improvements in hood fasteners for automobiles, and the primary object thereof is to provide a fastener which cooperates with the usual hand grips, or handles that are secured to the hood and are employed to enable manual lifting of the hood, thus dispensing with the necessity of employing an extra set of handles on the hood.

Further the invention aims to provide a fastener in which upon release thereof, the hands of the operator will be alined with and consequently immediately accessible to, the handles to thereby raise the hood, thus eliminating the necessity of the operator making further movement of his hands to grip the handles, after release of the fastener.

Still further the invention aims to provide a fastener which eliminates rattling especially in cases where the handles are located high up on the hood.

The invention further aims to provide a fastener which is of simple and economical construction and which has the advantages and other objects hereinafter pointed out and manifested in the course of the following description.

In the drawings: Figure 1 is a front elevation of the invention applied to a hood, the latter shown in fragment; Fig. 2 is a section on the line 2—2 of Fig. 1; Fig. 3 is a detail view showing one of the handles in top plan; Fig. 4 is a fragmentary detail view, partly in section of a modified form of head of the fastener; Fig. 5 is a detail, partly in section of a still further modified form of the invention.

The hood designated 1, in the drawings, has the usual general type of hand lifts, or handles 2, attached thereto, the latter being modified to the extent that each of same is provided with a transverse slot 3 which terminates in a seat 4, which latter is depressed

below the plane of the top face of the handle, as shown in Fig. 2.

The fastener consists of a shank 5, having a foot 6 which latter is movably confined within an outwardly or upwardly extending 60 socket 7 formed in a base plate 8, which latter is secured to the automobile body. A slot 9 is formed in the socket 7 to allow the shank to move through the slot toward and away from the hood 1. The upper end of 65 the shank is inclosed by a tubular member 10, the lower or bottom end of which member is rounded at 11 so as to engage conformably in the seat 4, the rounded bottom being perforated to permit the passage of 70 the shank or stem 5 therethrough. A washer 12 is placed over the shank 5, and is held thereon against upward or outward movement by a cross pin 13, which is passed through an opening provided therefor in 75 the shank, the under face of the washer being engaged by a coil spring 14, the lower end of which latter seats on the rounded bottom 11, of the member 10.

The upper end of the member 10, is 80 flanged at 15, and receives a top plate 16 thereon, the edges of which top plate are spun around the flange 15 to thus provide a closure and a peripheral outwardly extending hand grip for the upper end of the 85 member 10.

From the above it will be seen that to release the fastener, it is merely necessary to grip the head thereof and raise same against the tension of the spring 14, whereupon the rounded bottom 11, is moved out of the seat 4, and the member 10, may be then swung outwardly and moved out of the slot 3, so as to be entirely disengaged from the handle 2, it being understood that there 95 are two fasteners and two handles for each hood, the fasteners being located at the respective ends of the hood. After the movable locking means, above described, has been disengaged from the handle 2, it will 100 be noted that the hands of the operator are then beneath the handles 2, and in a position to grip same without any further appreciable movement of the hands, which is a matter of extreme convenience and enables the fasteners to be unlocked and the hood raised 105 easily and quickly.

In Fig. 4 of the drawings, a modified form of hand grip for the member 10, is provided in which the upper end of the mem- 110

ber is threaded and engaged with a cap 17 which latter closes the upper end of the member and has a hand engaging ring 18 formed thereon.

5 In Fig. 5 is shown a slightly modified form of the invention, in which the shank 5 is threaded and provided with a nut 19 which acts to enable tensioning of the spring 14.

10 The handles thus perform a dual function in that they provide keepers for the fasteners, and also act as the usual hand grips whereby the hood may be raised.

What is claimed is:

15 1. In a hood fastener, a hand grip for securing to the hood having a slot which terminates in a depressed seat to form a

keeper, a shank for connection to the automobile movable into said slot, and a spring held member slideable on the shank and having a part to engage in said seat.

2. In a hood fastener, a hand grip for the hood having an upwardly facing keeper, and a fastener element movably connected at a point below said grip and movable to engage the keeper.

In testimony whereof I affix my signature in presence of witnesses.

NORMAN W. CUMMINS.
